FOREIGN PATENT DOCUMENTS

EM 005310299-0001 * 6/2018

Primary Examiner — Paula Allen Greene*(74) Attorney, Agent, or Firm* — Conley Rose, P.C.; Grant Rodolph(57) **CLAIM**

The ornamental design for a headphone, as shown and described.

DESCRIPTION

FIG. 1 is a first perspective view of a headphone;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The design which is claimed is shown in solid lines in the drawings. The broken lines shown in the drawings depict portions of the environment, and form no part of the claimed design.

1 Claim, 8 Drawing Sheets(56)
